UNITED STATES PATENT OFFICE.

ASHER BUSSERT, OF AMANDA, OHIO.

THRESHOLD.

SPECIFICATION forming part of Letters Patent No. 448,501, dated March 17, 1891.

Application filed August 7, 1890. Serial No. 361,253. (No model.)

To all whom it may concern:

Be it known that I, ASHER BUSSERT, a citizen of the United States, and a resident of Amanda, in the county of Fairfield and State 5 of Ohio, have invented certain new and useful Improvements in Thresholds; and I do hereby declare that the following is a full, clear, and exact description of the invention, which will enable others skilled in the art to which 10 it appertains to make and use the same, reference being had to the accompanying drawings, which form a part of this specification.

My invention relates to improvements in thresholds designed to be applied to the out- 15 side doors of houses to prevent the entrance of water underneath the door.

In the ordinary construction of doors for houses much annoyance is caused by the entrance of water underneath the same in times 20 of storms, whereby the carpets and floors are injured or damaged. Many attempts have been made to provide means whereby this objection could be obviated, but all have proved more or less unsuccessful, owing to defects in 25 construction and operation, the high cost of the devices, or other causes, whereby they have not been introduced into general public use.

The object of my invention is to provide a 30 simple, economical, efficient, and reliable threshold which can readily be applied to a door and which will effectually prevent the entrance of water in times of storms.

The invention consists in the novel con- 35 struction and combination of parts hereinafter fully described, and definitely pointed out in the claim.

In the accompanying drawings, Figure 1 represents a perspective view of a door-frame 40 and door with my improved threshold applied thereto. Fig. 2 is a cross-section through the center of the threshold, showing also the lower portion of a door. Fig. 3 is a perspective view of the removable sill, looking from the under 45 side. Fig. 4 is a detail perspective view of the trough.

In the said drawings, the reference-numeral 1 designates the floor of a house; 2, the up- 50 right side pieces of the door-frame; 3, the lin- tel, and 4 the door, all of which may be of any ordinary or suitable construction.

The numeral 5 designates the interior door-sill, which is designed to be permanently secured to the floor. This sill is beveled rearwardly with a short horizontal portion 6 and 55 a vertical front wall 7. Secured to this front wall 7 is a trough 8, composed of a metal plate having an upwardly-projecting flange 9 ex- 60 tends from its sides and inner end. The rear half of this trough is somewhat wider than the front thereof, and the ends project- 65 ing outwardly at each side of the flange are beveled, as seen at 9' in Fig. 4. The object of making one portion of this trough wider than the other is to receive and hold the re- 70 movable or outer sill 10. This sill consists of a piece of wood of a width equal to the width of the door-frame and has a horizontal top wall 12 and beveled front end 13, and is pro- 75 vided with a projecting shoulder 14 at each side, which fits into the enlarged portion of the trough 8. The under side of this sill is provided with a series of longitudinal grooves 15, which extend from side to side thereof or entirely across the same.

The operation will be readily understood. The trough 8 is secured to the sill 5 by nails, screws, or other fasteners and the removable sill 10 inserted therein. Any water which may be driven under the door will escape be- 80 tween the flange 9 and sill 10, as there is a slight space between these parts, and will flow down and out through the grooves 15 on the under side of the sill 10, and thus be prevented from entering the floor or carpet.

Having thus described my invention, what I claim is—

The combination, with a trough having an enlarged inner portion and upwardly-projecting flange, of a sill having horizontal top edge, 90 beveled front, projecting shoulders at each side to fit in the enlarged portions of the trough, and horizontal grooves on its under side which extend entirely across the same, substantially as described.

In testimony that I claim the foregoing as my own I have hereunto affixed my signature in presence of two witnesses.

ASHER BUSSERT.
